JONATHAN MOORE AND WILLIAM WILKINSON, OF BROOKLYN, NEW YORK,
ASSIGNORS TO JONATHAN MOORE AND A. HORTON, OF SAME PLACE.

Design No. 4,804, dated April 11, 1871.

DESIGN FOR AN ORNAMENT FOR FOUNTAINS, &c.

The Schedule referred to in these Letters Patent and making part of the same.

We, JONATHAN MOORE and WILLIAM WILKINSON, of Brooklyn, in the county of Kings, State of New York, have invented and produced a new and original Design for Ornament on Fountains and Vases, of which the following is a specification.

Our design we may distinguish for convenience by the term "acanthus flutes and scallops." It is composed of a large classic leaf superimposed upon a series of flutings with rounded ends. The upper ends of these flutings form a scalloped edge for the vase or fountain. The contours and arrangements of the several members are fully represented in the accompanying drawings, to which reference is made.

Figure 1 is an outline of the contours of the several members, and

Figure 2 is a photographic illustration, giving a fuller view of the complete work.

The work will ordinarily be made in cast-iron, painted, bronzed, or otherwise protected, but the design is equally applicable to work in other materials.

We claim as our invention—

The design herein shown, which we may denominate acanthus flutes and scallops, for ornamentation of fountains and vases.

In testimony whereof we have hereunto set our names in presence of two subscribing witnesses.

JONATHAN MOORE.

Witnesses: WILLIAM WILKINSON.

JAMES DENBIGH,
BENJAMIN MORRISON.
